Primary Examiner — Antoine D Davis*(74) Attorney, Agent, or Firm* — Studebaker & Brackett PC(57) **CLAIM**

The ornamental design(s) for a contact probe, as shown and described.

DESCRIPTION

FIG. 1 is a perspective view of the front, top and left side of a contact probe of a first embodiment showing our new design; FIG. 2 is a perspective view of the rear, top and right side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of tip side from 9-9 section in FIG. 1 thereof;

FIG. 10 is an enlarged view of tip side from 10-10 section in FIG. 2 thereof;

FIG. 11 is an enlarged view of tip side from 11-11 section in FIG. 3 thereof; and

FIG. 12 is an enlarged view of tip side from 12-12 section in FIG. 6 thereof;

FIG. 13 is a perspective view of the front, top and left side of a contact probe of a second embodiment showing our new design;

FIG. 14 is a perspective view of the rear, top and right side thereof;

FIG. 15 is a front view thereof;

FIG. 16 is a rear view thereof;

FIG. 17 is a left side view thereof;

FIG. 18 is a right side view thereof;

FIG. 19 is a top view thereof;

FIG. 20 is a bottom view thereof;
FIG. 21 is an enlarged view of tip side from 21-21 section in FIG. 13 thereof;
FIG. 22 is an enlarged view of tip side from 22-22 section in FIG. 14 thereof;
FIG. 23 is an enlarged view of tip side from 23-23 section in FIG. 15 thereof; and
FIG. 24 is an enlarged view of tip side from 24-24 section in FIG. 18 thereof;
FIG. 25 is a perspective view of the front, top and left side of a contact probe of a third embodiment showing our new design;
FIG. 26 is a perspective view of the rear, top and right side thereof;
FIG. 27 is a front view thereof;
FIG. 28 is a rear view thereof;
FIG. 29 is a left side view thereof;
FIG. 30 is a right side view thereof;
FIG. 31 is a top view thereof;
FIG. 32 is a bottom view thereof;
FIG. 33 is an enlarged view of tip side from 33-33 section in FIG. 25 thereof;
FIG. 34 is an enlarged view of tip side from 34-34 section in FIG. 26 thereof;
FIG. 35 is an enlarged view of tip side from 35-35 section in FIG. 27 thereof; and

FIG. 36 is an enlarged view of tip side from 36-36 section in FIG. 30 thereof,
FIG. 37 is a perspective view of the front, top and left side of a contact probe of a fourth embodiment showing our new design;
FIG. 38 is a perspective view of the rear, top and right side thereof;
FIG. 39 is a front view thereof;
FIG. 40 is a rear view thereof;
FIG. 41 is a left side view thereof;
FIG. 42 is a right side view thereof;
FIG. 43 is a top view thereof;
FIG. 44 is a bottom view thereof;
FIG. 45 is an enlarged view of tip side from 45-45 section in FIG. 37 thereof;
FIG. 46 is an enlarged view of tip side from 46-46 section in FIG. 38 thereof;
FIG. 47 is an enlarged view of tip side from 47-47 section in FIG. 39 thereof; and
FIG. 48 is an enlarged view of tip side from 48-48 section in FIG. 42 thereof.

The portions of the article in broken lines are shown for illustrative purposes only and form no part of the claimed design.
